UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,177,875.

Specification of Letters Patent.

Patented Apr. 4, 1916.

Original application filed January 9, 1912, Serial No. 670,136. Divided and this application filed June 27, 1913. Serial No. 776,008.

To all whom it may concern:

Be it known that I, ALFRED G. F. KUROWSKI, a citizen of the United States, residing in Brooklyn borough, in the county of Kings, city and State of New York, have invented certain new and useful Improvements in Type-Writing Machines, of which the following is a specification.

This invention relates to typewriting machines, in which a relative shifting movement is effected between the types and the platen to enable either lower case or capital letters to be written, and particularly to those machines in which the platen remains stationary while the type-bars are shifted up and down.

This application is a division of my co-pending application Serial Number 670,136, filed January 9, 1912 which has now matured into Patent No. 1,144,766, June 29, 1915.

An object of the invention is to provide improved means for shifting the type-bar segment or carrying frame, which shall be simple in construction and accurate in operation and which will securely lock said segment or frame in both upper and lower case positions.

Another feature of the invention resides in the improved anti-friction means for guiding the type-bar frame in its vertical movements.

The segment which carries the type-bars is mounted on a frame shiftable to upper and lower case positions by means of shift key levers, each of which has a hook or projection extending over a wrist pin on a rock arm, said rock arms being upon a rock shaft extending across the machine beneath the type-bar segment. On said rock shaft are arms having cam slots in which work wrists carried by the segment frame, said slots being shaped to give an up-and-down movement to the segment frame when the shaft is rocked, the slots also having dwell portions to lock the segment frame in its raised and lowered positions. Said frame is guided between vertical plates adjustable toward and from the frame to take up play; anti-friction rollers being interposed between said plates and said frame.

Between the type-bars and key-operated bell cranks on the machine frame are interposed individual slides having pin-and-slot

connections with the type-bars, and also having pin-and-slot connections with the bell cranks to permit vertical movement of said members relative to the bell cranks when the type-bar segment is shifted up and down, also permitting transverse movement of said members to actuate the type-bars during the printing strokes.

Other features and advantages will appear hereinafter.

In the accompanying drawings, Figure 1 is a sectional side elevation of a type-bar and connected parts in printing position, the shiftable segment being in its lower case position. Fig. 2 is a sectional side elevation taken about midway from front to rear, of an Underwood typewriting machine, modified in accordance with the present improvements, the parts being shown in their normal position of rest. Fig. 3 is a view similar to Fig. 1, but showing the parts shifted for writing capitals. Fig. 4 is a fragmentary view of one of the slideable portions of the type-bar segment. Fig. 5 is a sectional front elevation view of the type-bars, type-bar segment, and connected parts. Fig. 6 is a side elevation view of one of the guides and roller bearings for the shiftable type-bar segment. Fig. 7 is a perspective view of a type-bar and the slide connecting it to a bell crank. Fig. 8 is a sectional view showing a leg of the segment frame, a guide plate and a roller bearing. Fig. 9 is a sectional front elevation of the right-hand portion of the segment frame and the adjustable guide therefor. Fig. 10 is a diagrammatic front elevation view of a type-bar, bell crank and a connection between them.

Type-bars 1 are pivoted upon a common fulcrum rod 2 and guided in radial slots 3 in a segment 4 to strike upwardly and rearwardly against the front side of a platen 5. The type-bars normally rest upon a pad 6 supported by a basket 7 on rods 8 extending forwardly from the segment 4. Each type-bar carries a lower case type 9 and a capital type 10. The type-bar segment is shifted upward by means of shift keys 11, each mounted on the forward end of a lever 12 which has an arm or hook 13 to extend over a wrist 14 on a crank arm 15 projecting forward from a horizontal rock shaft 16, whereby the shaft 16 is rocked when the shift key is depressed. The shaft 16 ex-

tends across the machine beneath the type-bar segment, and is journaled at its ends in lugs 17 (Fig. 5) on the machine frame.

The rock shaft 16 carries a pair of arms 18 near its ends, said arms being provided with cam slots 23 to receive the wrists 19 projecting from legs 20 of the type-bar segment frame 21, for shifting the type-bars to upper and lower case positions. The segment 4 is secured to the frame 21 by screws 22. The cam slots 23 are of such shape that when the arms 18 are swung forward by the depression of either shift key, the wrists 19 will be cammed upward, thereby shifting 15 the type-bar segment from lower to upper case position.

As seen in Fig. 1, the wrists 19 normally occupy dwell portions 24 in the forward ends of the slots to lock the segment against upward movement, the portion 24 of the slot being substantially concentric with the shaft 16. The opposite end of each cam slot also comprises a dwell portion 25 substantially concentric with the shaft 16 so that the type-bar segment is locked in its upper case position, as shown in Fig. 3. The dwell portions form a positive means for preventing any shake or movement of the type-bar segment while in either upper or lower case position.

On the machine frame are stop lugs 26 in the path of upper and lower stops 27 and 28 secured to the segment frame 21. The lugs 26 are preferably secured to the frame by means of screws 262 in the slots 261 formed in said lugs. The segment frame is guided by pairs of anti-friction rolls 29, each pair comprising an upper and a lower roll journaled in a vertical carriage 30 moving with the segment and occupying vertical grooves 31 and 32, the grooves 31 being formed in the outer sides of the legs 20 and the grooves 32 formed in the inner sides of a pair of plates 33 adjustably secured to the machine frame for taking up play, and permitting 45 the lateral adjustment of the segment frame. Each groove has converging walls 34 (see Fig. 8), and the ends of the rolls 29 are beveled or coned to fit these converging walls.

Each plate 33 has a vertical tongue 35 to fit in a groove 36 formed in a part 37 of the framework of the typewriter, thus firmly supporting and guiding the plate 33 and permitting it to be adjusted to take up play in the roller bearings. Each plate 33 is adjustably secured by means of screws 38 threaded through the frame 37 and bearing against the plate 33. The plate is securely held in adjusted position by screws 39 extending through the machine frame 37, and threaded 55 into plate 33, the screws 39 being set up to clamp the plate 33 against the adjusting screws 38 after the plate 33 has been adjusted.

Each carriage 30 to which the rolls are journaled by pintles 40 has a horizontal projection 41 at its upper end to rest on the top

of the plate 33 and support said carriage in its normal position. Each carriage is movable upward or downward as the segment rises or falls. Upon the shaft 16 is a coiled spring 42 which partly counterbalances the weight of the segment and type-bars, said segment being returned by gravity from upper to lower case position. The spring 42 is secured at one end of the machine frame, and at its opposite end to an adjusting sleeve 42a on the shaft 16, whereby the tension of the spring may be regulated. A return spring 43 may be connected to one of the arms 18 to assist in returning said arm and the rock shaft 16 to lower case position, and to assist in lowering the type bar segment.

The type-operating keys 44 are mounted on levers 45 similar in form to the levers 12 and fulcrumed on the same bar 46, the levers 12 and 45 having returning springs 47. Upon the key levers 45 are wrists 48 to engage slots 49 in the horizontal arms 50 of bell cranks 51. The bell cranks have upright arms provided with wrists 52 to engage slots 53 extending up and down in arms 54 provided on slides 55 which form connections between the bell cranks and type-bars, for swinging the latter about their fulcrum 2. The slides 55 have wrists 56 to engage cam slots 57 in the type-bars 1, so that when a slide is moved forwardly by its bell crank, a type-bar is swung up to printing position. The slides 55 occupy recesses or enlargements 59 in the radial type-bar slots 3, and lie side by side with the type-bar hubs in the enlarged portions of the slots, said slots therefore serving to guide the slides as well as the type-bars. The arms 54 of slides 55 extend beyond the recesses 59 and are bent 105 to be parallel to or substantially in line with the upper arms of their respective bell cranks 51 the horizontal arms of which bell cranks are in turn parallel to or substantially in the same planes as the key levers, 110 so that arms 54 and the key levers are practically in the same planes. The guides in a sense, form adjustable extensions of the upper ends of the bell cranks.

In Fig. 4 is shown the conformation of the lower portion of the segment 4, and the manner in which the type-bar fulcrum rod 2 is mounted, as well as the front and rear curved rods 61 and 60 upon which the slides 55 are guided, all of said rods being seated 120 in slots in the segment, the inner ends of the slots being enlarged to fit the rods and retain them in place. The slides 55 are provided with slots 62 and 63 through which the guide rods 61 and 60 extend, said slots 125 being preferably formed on a curve substantially concentric with the fulcrum 64 of the bell cranks 51, whereby the slide 55 is given a curvilinear motion when actuated by the bell crank, so that the wrist 56 on the slide 130

will have the desired action upon the type-bar. That is, the direction of movement of the wrist 56 is first approximately in the direction of the slot 57, so that the type-bar is started slowly in motion, and then transversely of the slot, so that the type-bar is speeded as it approaches the platen.

Variations may be resorted to within the scope of the invention, and portions of the 10 improvements may be used without others.

Having thus described my invention, I claim:

1. The combination with an up-and-down shiftable type segment, guiding legs depending from said segment, ways on the machine on which ways said legs are guided straight up and down, of a rock shaft, extending across the machine, a key to operate said rock shaft, arms on said rock shaft, 15 connections between said key and said rock-shaft, and wrists on said guiding legs operable by said arms to shift the segment straight up and down, said arms having cam slots engaged by said wrists, and 20 formed both to lock the segment against movement in either direction from normal position and to shift the same.

2. The combination with an up-and-down shiftable type segment, downwardly projecting legs on said segment, ways on the machine frame, means on said legs for fitting said ways, a rock shaft extending across the machine, a key, connections between said key and said rock-shaft to operate said rock shaft, arms on said rock shaft, wrists on said segment operable by said arms to shift the segment straight up and down, said arms having cam slots engaged by said wrists both to lock the segment in normal position and to shift the same, and also to lock the segment in shifted position, and adjustable stops for said segment.

3. The combination with an up-and-down shiftable type segment, depending legs on said segment, grooves on the frame, means on said legs engaging said grooves, a rock shaft extending across the machine, of a key, connections between said key and said rock-shaft to operate said rock shaft, arms on said rock shaft, wrists on said segment operable by said arms to shift the segment straight up and down, said arms having cam slots engaged by said wrists both to lock the segment in normal position and to shift the same, and also to lock the segment in shifted position, a returning spring for said arms, and a counter-balancing spring for said segment.

4. A shiftable type bar segment having on its opposite edges guiding grooves, guiding members on the framework of the machine having corresponding guiding grooves, said grooves extending up and down, and each groove having converging guide walls,

the grooves coöperating to form races, upper and lower rolls in each race having parallel axes between the grooves of said segment and those of said guiding members, each roll having bearing faces at its opposite ends each spanning the space between the segment and a guiding member, and carriages or spacers to which said rolls are pivoted, and which are movable up and down to permit the rolls to run up and down on their bearing surfaces.

5. A shiftable type bar segment having on its opposite edges guiding grooves, guiding members on the framework of the machine having corresponding guiding grooves, 80 said grooves extending up and down, and each groove having converging guide walls, the grooves coöperating to form races, upper and lower rolls in each race, said rolls having their axes perpendicular to the plane 85 of the segment and between the grooves of said segment and those of said guiding members, said rolls having bearing faces spanning the space between the segment and a guiding member, and carriages or 90 spacers to which said rolls are pivoted; one of said guiding members having a plate or member adjustable toward the segment to take up play of the rolls.

6. A shiftable type bar segment having 95 on its opposite edges guiding grooves, guiding members on the framework of the machine having corresponding guiding grooves, 100 said grooves extending up and down, and each groove having converging guide 105 walls, the grooves coöperating to form races, upper and lower rolls in each race, carriages or spacers to which said rolls are pivoted, one of said guiding members having a plate or member adjustable toward 110 the segment to take up play of the rolls, said adjustable plate having a vertical tongue, and the framework member having a corresponding groove, and oppositely acting screws for both adjusting the plate and securing it where adjusted.

7. In a typewriting machine, the combination with a type bar segment shiftable to upper and lower case positions guiding grooves therefor, means on said segment engaging said grooves of a rock shaft, an arm on said rock shaft having a cam slot therein, a wrist on the segment and working in said slot, a key to rock said shaft and connections from said key to said rock-shaft, said slot terminating in dwell portions substantially concentric with the rock shaft and at different distances from the rock shaft, and having an intermediate cam portion to shift the segment, said dwell portions each forming a lock to prevent either up or down movement of the type bar segment while the said wrist is in a dwell portion.

8. In a typewriting machine, the combi-

nation with a vertically shiftable type bar segment, of a shift key lever, a rock shaft, a rock arm on said shaft, a projection on said lever extending over said rock arm, 5 a second arm on said shaft formed with a cam slot, and a wrist on the segment working in said slot.

9. In a typewriting machine, the combination with a machine frame and a type-carrying frame shiftable vertically to upper and lower case positions, of a bearing plate having a connection with the machine frame comprising a vertical tongue and groove, means to adjust said bearing plate laterally and hold it in adjusted position, 15 and bearing rollers between said plate and the type-carrying frame.

10. In a typewriting machine, the combination with a machine frame and a type-carrying frame shiftable vertically to upper and lower case positions, of a bearing plate having a connection with the machine frame comprising a vertical tongue and groove, means to adjust said bearing plate laterally 20 and hold it in adjusted position, bearing rollers between said plate and the type-carrying frame, said means comprising screws threaded in the machine frame and bearing against the adjusting plate, and screws extending loosely through the machine frame and threaded into said adjusting plate.

11. In a typewriting machine, the combi-

nation of a shiftable type bar segment frame having on its outer edges vertical guiding 35 grooves, guiding members on the machine frame having opposing guiding grooves, said grooves having converging guide walls and forming races, upper and lower rolls in said races, said rolls having forwardly 40 and rearwardly extending horizontal axles, and carriages or spacers on which said axles are mounted.

12. In a typewriting machine, the combination with a shiftable type bar segment 45 having on its opposite edges guiding grooves, guiding members on the framework of the machine having corresponding guiding grooves opposite said first-named grooves extending vertically, each groove 50 having converging side walls, the grooves co-operating to form a recess, upper and lower rolls in said recess, each having a forwardly and rearwardly extending axis, the length of said rolls being greater than 55 their diameter, and each roll formed at its outer end with beveled or inclined bearing surfaces spanning the spaces between the segment and guiding member and bearing on said converging side walls, and spacing 60 carriages to which said rolls are pivoted.

ALFRED G. F. KUROWSKI.
